UNITED STATES PATENT OFFICE.

HORATIO P. VAN CLEVE, OF CRANFORD, NEW JERSEY, ASSIGNOR TO J. EDWARD OGDEN, OF MOUNTAINVILLE, NEW YORK.

SUPPORT FOR FERRY BRIDGES.

Application filed April 14, 1925. Serial No. 23,094.

This invention relates to improvements in moorings for ferryboats and supports for the bridges or hinged platforms over which passengers and freight pass to and from the boats. An arrangement for these purposes is shown in reissued Patent No. 14,313 issued to Francis L. DuBosque, June 5, 1917, and an object of this invention is to improve upon this DuBosque arrangement and more particularly to provide mechanism which will not be disturbed by wide tide level changes.

These and other objects of this invention will appear in the following specification in which an embodiment of the invention will be described and its novel features defined in claims.

Fig. 1 is a diagrammatic elevation of enough of the parts of a ferry bridge to illustrate this invention, together with its novel supporting mechanism and the actuating mechanism therefor.

Fig. 2 is a side elevation of the end of the bridge and of a boat with the mooring and supporting cables.

In the drawings, 10 designates the bridge, the inner end of which is hinged in the usual manner, so that the outer end, which is shown in the drawings may be moved up and down. 11, 11 are stationary parts of the dock at the sides of the bridge from which rise posts 12 which support beams 13 which extend across the bridge. The greater part of the weight of the bridge is balanced by counterweights 14 connected to the outer or free end of the bridge by chains or cables 15 which pass over sheaves 16 on the beams 13 and exert a lifting force of constant magnitude on the bridge.

20 is an auxiliary weight and 21 a spring supported receiving platform therefor. On the weight 20 is a plurality of sheaves 22. 23 is a traveling frame which pivotally supports the same number of sheaves 24 as are on the weight 20. One end of a chain or cable 25 is connected to the frame 23 which after passing under and over the sheaves 22, 24 extends to a winding drum 26 to which its other end is connected. Chains or cables 27, 27 pass from the frame 23 over sheaves 28 on the beams 13 and down to links 29.

From each of the links 29 two chains or cables extend downwardly. One of these, designated by 30, is connected to a turn-

buckle 31 from which an extension 32 runs down through a frame 33 pivotally supported on the bridge 10 at 34. This extension runs under a sheave 35 on the frame 33 and terminates in a loop or ring 36. A stop 37 is affixed to the cable extension 32 and is so arranged and positioned that it may engage the upper end of the frame 33 when the loop 36 is free.

The other chain or cable extending downwardly from link 28 is designated by 38, and this terminates in a loop or ring 39.

40 is an electric motor connected through proper mechanism for rotating the winding drum 26.

Except for the connections of the auxiliary weight 20, the apparatus so far described operates like the aforesaid DuBosque mechanism. The free end of the bridge is supported by the cables 15 and 27, the latter through the engagement of the stops 37 with the frames 33. The bridge may be lifted by causing motor 40 to rotate in a direction to raise weight 20 from its support 21, but as the weight is heavier than the unbalanced portion of the bridge it remains on its seat and the bridge rises. When the ferryboat, the end of which is shown in Fig. 2, designated by 17 is near or against the end of the bridge 10, the motor is actuated to slacken cables 27 and their extensions 30 and 38. The bridge will be lowered thereby until its bars 18 rest upon the deck of the boat. Then the loops or rings 36 and 39 are placed over hooks 19 on the boat and weight 20 raised.

The length of cable extensions 32 from stops 37 to rings 36 is such that their upward pull will be deflected by the pulleys 35 into a horizontal pull which will hold the boat up against the bridge while they still exert some lifting pull on the bridge. The cables 38 will exert a lifting pull on the boat and through the bars 18 will assist in carrying any load which passes over the bridge.

It is obvious that the cable extensions 32 may be used alone to advantage, and so too the cable extensions 38 may be used without the extensions 32.

With former devices, it has been found in some locations where there is considerable rise and fall of tide, that when a boat is moored for a long time, as for example, overnight, the path of movement of the auxiliary

weight 20 is too short and unless the motor 40 is actuated to release rope 25, this weight may be carried beyond the limits of its travel. With this invention a marker 25^A 5 is affixed to cable 25 which will indicate to the operator the amount of winding which would be on the drum 26 when the bridge and counterweight are in medial positions from which positions they can rise or fall 10 for the full range of the tide without causing the counterweight 20 to reach either of its limits of travel.

With this arrangement the mechanism may be left without an attendant and without the electrical control described later herein, during any period when the boat is moored to the bridge. The boat raises and lowers the bridge with the tide movement and causes an opposite movement of the 20 frame 23 and of the weight 20.

This device could be used alone, but it is obvious that each time a boat is unmoored, the weight 20 must be lowered to its seated position and at low tide this lowering distance would be too great to permit quick operation in mooring the boat if after each mooring operation the marker 25^A 25 is brought to the safe position. It is therefore preferable to ignore the position of marker 25^A and provide an automatic device to limit the up and down movements of this weight for different conditions of the tide so that the bridge can be held automatically close to its mooring 30 position when boats are being moored at short intervals. Such a device is now used for the night operation when a boat is continuously moored as well as for the day operation but it has been found that due to failures of the electric current, because of fuse blowouts or stoppage of the source of electrical supply, when the bridge is without an attendant, the weight 20 has been carried beyond its limits with disastrous results.

The device of this invention provides a safe alternate control for periods when the moored boat is left without an attendant.

It is obvious that if the rise of the tide should cause the weight 20 to seat on the 50 support 21, at a time when the marker 25^A is above its safe position, the cable connections to the boat will become slackened and may even become detached. To prevent this, a switch automatically actuated by the movement of the auxiliary weight may be provided. This comprises an arm pivoted at 41 and having spaced abutments 42, 43 arranged to be engaged by a pin 44 projecting from weight 20. This arm carries a switch blade 45 which by the movement of the weight 20 is moved into or out of engagement with stationary contacts 46, 47. These are so connected with the motor circuit as to start the motor, when they are closed, in a direction 60 to raise the weight, and so that a short up-

ward movement of the weight will open the contacts and stop the motor.

Combined with this automatic switch are other switches and circuits for the control of the motor, which will now be described.

50 is the movable blade of a master switch, which is connected with the positive lead from a power supply and which may be moved manually into engagement with a stationary contact 51, connected with contact 75 46 of the automatic switch or with a stationary contact 52 connected with the movable blade 53 of a reversing switch and to contact 47 of the automatic switch. The other or negative lead from the power supply is connected to the other movable blade 54 of the reversing switch. It is to be understood that the blades 53, 54 are mechanically connected to move together and that they cooperate with stationary contacts and 80 motor connections in a manner so well understood that no detailed description is necessary, to cause the motor 40 to rotate in a direction to lift weight 20, when they are moved to the right and in a direction to lower weight 20, when they are moved to the left.

When the master switch is moved to the left, the reversing switch is energized, and the operator can cause weight 20 to be raised or lowered at will, as will be done in mooring or releasing the boat. When the master switch is moved to the right, the reversing switch is energized only when the automatic 90 switch is closed.

An interlock mechanism for the switches is provided, which will now be described. The switch blades 50, 53, 54 are pivoted on a common axis. 55 is a transverse bar of insulating material affixed to blade 50 and extending back of blades 53, 54. When the reversing switch is to be actuated, the switch blade 50 will be in engagement with contact 52 so the bar 55 will not interfere with the movement of the blades 53, 54. When the 100 automatic switch is to be made operative, the blade 50 of the master switch is moved over into engagement with contact 51. This will move bar 55 to the right and it will move blades 53, 54 of the reversing switch 105 into engagement with the contacts which are provided for imparting a weight lifting rotation to the motor. Obviously the motor will then be energized and deenergized by the closing and opening of the automatic 115 switch.

Another interlock is provided by securing a similar bar 56 to blades 53, 54 which has no effect when the blades are in the positions shown in the drawings, but which will 125 move blade 50 of the master switch into engagement with contact 52 when the operator moves the blades of the reversing switch to the left to cause the motor to lower weight 20.

With this arrangement the operator may lower and raise weight 20 at will in mooring the boat. When this is done he will leave weight 20 in a position slightly above its support 21 and then throw the master switch over to the right. The mechanism will then take care of itself if an accidental stoppage of the electric current does not occur.

10 In the arrangement shown by DuBosque, the movement of the auxiliary weight is twice as great as that of the bridge. But it is possible, by means of the present invention, to decrease the relative movement between the bridge and the auxiliary weight 20. The reducing mechanism between the frame 23 and the weight 20 causes the movement of the auxiliary weight to be but slightly greater than that of frame 23 which is the same in degree as that of the part 20 of the bridge with which the cables 27 are connected. Therefore, when the marker 25^A is in mid-position the boat may remain moored indefinitely without need of actuating motor 40 so long as the tide variations do not cause the movement of weight 20 to be greater than that provided for its travel.

Moreover, the interposition of reduction mechanism between frame 23 and weight 20 makes it possible to use a smaller motor and a lighter rope or cable on the winding drum.

The mechanism shown is more or less diagrammatic and many changes and modifications may be made within the scope of the invention, but what is believed to be new is defined in the following claims.

What I claim is:

1. The combination with a ferry bridge, of means for mooring a ferryboat thereto comprising a stationary overhead sheave, a weight, a lifting mechanism therefor, a cable running over the overhead sheave and having one end arranged to be connected to a boat, and reduction mechanism interposed between the other end of the cable, the weight and the lifting mechanism.

2. The combination with a ferry bridge, of means for mooring a ferryboat thereto comprising connections to the bridge and the boat, a stationary overhead sheave, a weight, a lifting mechanism therefor, a cable running from the said connections and over the overhead sheave and reduction mechanism interposed between the other end of the cable, the weight and the lifting mechanism.

3. The combination with a ferry bridge, of means for mooring a ferryboat thereto comprising a sheave near the end of the bridge, a stationary overhead sheave, a weight, a lifting mechanism therefor, a cable running over the overhead sheave having a branch arranged to be connected directly to a boat and a branch running under the bridge sheave and arranged to be connected with the boat and multi-pulley block

mechanism interposed between the other end of the cable, the weight and the lifting mechanism.

4. The combination with a ferry bridge, of means for mooring a ferryboat thereto comprising a stationary overhead sheave, a weight having a plurality of sheaves thereon, a lifting mechanism, a cable running over the overhead sheave having one of its ends arranged to have a bifurcated connection to the bridge and the boat and a plurality of sheaves at its other end, a lifting mechanism, and a cable running under the weight sheaves, over the sheaves at the end of said first mentioned cable and having its ends connected with the lifting mechanism and with said first mentioned cable.

5. The combination with a ferry bridge, of means for mooring a ferryboat thereto comprising a sheave near the end of the bridge, a stationary overhead sheave, a weight having a plurality of sheaves thereon, a lifting mechanism, a cable running under the bridge sheave, over the overhead sheave having one of its ends arranged to be connected to a boat and a plurality of sheaves at its other end, a lifting mechanism, and a cable running under the weight sheaves, over the sheaves at the end of said first mentioned cable and having its ends connected with the lifting mechanism and with said first mentioned cable.

6. The combination with a ferry bridge, of means for mooring a ferryboat thereto comprising a stationary overhead sheave, a weight, a lifting mechanism therefor comprising an electric motor, a cable running over the overhead sheave and having one end arranged to be connected to a boat, and reduction mechanism interposed between the other end of the cable, the weight and the lifting mechanism, circuits for the motor and a switch arranged to be actuated automatically by the movement of the weight for controlling said motor circuits.

7. The combination with a ferry bridge, of means for mooring a ferryboat thereto comprising a stationary overhead sheave, a weight having a plurality of sheaves thereon, a lifting mechanism comprising an electric motor, a cable running over the overhead sheave having one of its ends arranged to be connected to a boat and a plurality of sheaves at its other end, a lifting mechanism, and a cable running under the weight sheaves, over the sheaves at the end of said first mentioned cable and having its ends connected with the lifting mechanism and with said first mentioned cable, circuits for the motor and a switch arranged to be actuated automatically by the movement of the weight for controlling said motor circuits.

In witness whereof, I have hereunto set my hand this 7th day of April, 1925.

HORATIO P. VAN CLEVE.
